(57) **CLAIM**

The ornamental design for a fireplace with narrow vent, as shown and described.

DESCRIPTION

FIG. 1 is a perspective view of a first embodiment of a fireplace with narrow vent showing my new design;

FIG. 2 is a front elevation view of the first embodiment;

FIG. 3 is a top plan view of the first embodiment;

FIG. 4 is a rear elevation view of the first embodiment;

FIG. 5 is a bottom plan view of the first embodiment;

FIG. 6 is a left side elevation view of the first embodiment;

FIG. 7 is a right side elevation view of the first embodiment;

FIG. 8 is a front perspective view of a second embodiment of a fireplace with narrow vent showing my new design; and,

FIG. 9 is a front elevation view of the second embodiment.
